his ATTORNEYS

UNITED STATES PATENT OFFICE.

EDGAR MAYNARD CAMP, OF NEWARK, NEW JERSEY, ASSIGNOR, BY MESNE ASSIGNMENTS, TO WILLIAM D. BLEICK, OF NEWARK, NEW JERSEY.

DASH-POT.

1,394,063.

Specification of Letters Patent. Patented Oct. 18, 1921.

Application filed November 17, 1919. Serial No. 338,599.

To all whom it may concern:

Be it known that I, EDGAR MAYNARD CAMP, a citizen of the United States, and a resident of Newark, in the county of Essex and State of New Jersey, have invented certain new and useful Improvements in Dash-Pots, of which the following is a specification.

My present invention relates to dash-pots and more particularly to dash-pots suitable for use in adding machines and like mechanisms in which fluid, such as oil, is forced from one side of a piston to the other by the relative movement between the piston and the coacting cylinder or casing.

One object of my invention is to provide a dash-pot having new and novel means for adjusting the size of the port through which the liquid must flow from one side of the piston to the other, and thus regulating the speed or the number of strokes per minute which can be obtained with a given amount of power driving the device.

A feature of the present invention consists in having the aforesaid adjusting means on the outside of the apparatus and thus easy of access to the operator.

Another feature of the invention is the provision of a dash-pot in which the closing or working stroke is slower under the same power than the opening or return stroke.

Other objects, features and advantages will appear more fully in the following detailed description and appended claims.

The accompanying drawing, forming a part of this specification, illustrates one embodiment of the invention.

In the drawing,

Figure 1 is a view partly in section and partly in elevation showing the dash-pot at the limit of its thrust.

Fig. 2 is a like view showing the dash-pot with the port in an open position.

Fig. 3 is an enlarged view partly in section and partly in elevation of the port or valve parts in the same position as shown in Fig. 1.

Referring to the drawing, a cylindrical pot or casing 1, containing a suitable fluid 2, is pivoted at 3 on an actuating arm 4 on a rockshaft 5. The pot or casing 1 is provided with a cap 6, through which passes slidably a sleeve 7 surrounding and slidably along a

rod 8 secured into a bearing 9 pivoted upon a fixed center or shaft 10. On the lower end of the sleeve 7 is secured a piston head 11. The sleeve 7 is provided with a longitudinal slot 7^a near its lower extremity which embraces a pin 12 fixed in the rod 8 and the walls of which limit the downward movement of the sleeve 7 on said rod 8. The rod 8 is threaded downward a suitable distance at 8^a from the point where it is secured into the bearing 9, and carries on its threaded portion outside of the pot 1 two lock and adjusting nuts 13, which may be knurled to facilitate the easy adjusting of same by hand. The nuts 13 limit the upward movement of the sleeve 7 on the rod 8.

In operation, the slot 7^a functions as a port to regulate the passage of the fluid 2 which, during the working or compression stroke, passes from the part 1^a of the chamber below the piston head 11 to the part 1^b of said chamber above the piston head 11, the fluid 2 entering the sleeve 7 at the lower end 7^b, which opens to the space below the piston head and passing through said port 7^a, which is arranged above the piston head. During the said stroke, in the form of the invention shown, the casing or pot 1 moves upwardly relatively to the piston head 11, and the top 7^c of the sleeve 7 will be forced up against the nuts 13, as in Fig. 1, thus closing the port 7^a to the proper point. Should it be desired to close the port 7^a further, the nuts 13 should be positioned higher on the threaded portion 8^a of the rod 8 and vice versa.

During the opposite stroke, shown in Fig. 2, the direction of the fluid is changed and it passes from part 1^b of the chamber, through the port 7^a, through the end 7^b of the sleeve 7 and into the part 1^a of the chamber. The pressure of the fluid during this movement forces the sleeve 7, which is free to move on the rod 8 to drop to the limit allowed by the pin 12 and thus opens the port 7^c to its widest capacity, thereby allowing a quick return of the parts to their original position. It will be seen that during the return stroke a constant speed, not affected by the adjusting means, is given to the device. The speed in the opposite direction, however, that is the closing speed of the dash-pot can be regulated to be the

same as the opening speed, or any lower speed desired within the limits for which the device is built.

While I have shown one embodiment of the invention, it is to be understood that I am not limited thereto and that many changes and modifications may be made therein without departing from the spirit of my invention.

10 Having thus described my invention, what I claim, and desire to secure by Letters Patent is:—

1. The combination of a casing having fluid therein, and means including a piston mounted therein to permit relative reciprocable movement between the casing and piston, said means having a port permitting the flow of fluid from one side of the piston to the other, and means controlling the size of said port and opening the port to a greater extent on one stroke than on the opposite stroke whereby the retarding action of the fluid against such relative movement is greater for one stroke than the opposite stroke, said port controlling means being adjustable to vary the size of the port for one of said strokes.

2. The combination of a casing having fluid therein, and means including a piston mounted therein to permit relative reciprocable movement between the casing and piston, said means having a port permitting the flow of fluid from one side of the piston to the other, and means controlling the size of said port and opening the port to a greater extent on one stroke than on the opposite stroke, whereby the retarding action of the fluid against such relative movement is greater for one stroke than the opposite stroke, said port controlling means having means arranged exteriorly of the casing for varying the size of the port for one of said strokes.

3. The combination of a casing having fluid therein, and means including a piston mounted therein to permit relative reciprocable movement between the piston and casing, said means having a port permitting the flow of fluid from one side of the piston to the other, and means controlling the size of said port and opening the port to a greater extent on one stroke than on the opposite stroke, whereby the retarding action of the fluid against such relative movement is greater for one stroke than the opposite stroke, said port controlling means having means arranged exteriorly of the casing for varying the size of the port for the stroke with the greater retarding action.

4. The combination of a casing having a fluid therein, a piston in said casing, and a pair of telescopically connected members, one of which is connected to said piston and the other of which projects out of said casing, one of said members having a port

by which said fluid may pass from one side of said piston to the other, the other of said members being free to have a limited longitudinal movement with respect to the ported member to vary the extent of opening of said port, whereby said port is open to a greater extent upon one stroke than upon the opposite stroke.

5. The combination of a casing having a fluid therein, a piston in said casing, and a pair of telescopically connected members, one of which is connected to said piston and the other of which projects out of said casing, one of said members having a port by which said fluid may pass from one side of said piston to the other, the other of said members having a limited longitudinal movement with respect to the ported member to vary the extent of opening of said port, whereby said port is open to a greater extent upon one stroke than upon the opposite stroke, and one of said members having means for varying the extent of such limited longitudinal movement.

6. The combination of a casing having a fluid therein, a piston in said casing, and a pair of telescopically connected members, one of which is connected to said piston and the other of which projects out of said casing, one of said members having a port by which said fluid may pass from one side of said piston to the other, the other of said members having a limited longitudinal movement with respect to the ported member to vary the extent of opening of said port, whereby said port is open to a greater extent upon one stroke than upon the opposite stroke, one of said members having means adjustable outside of said casing for varying the extent of such limited longitudinal movement.

7. The combination of a casing having a fluid therein, a piston in said casing, and a pair of telescopically connected members, one of which is connected to said piston, one of said members having a port by which said fluid may pass from one side of said piston to the other, the other of said members having a limited longitudinal movement with respect to the ported member to vary the extent of opening of said port, whereby said port is open to a greater extent upon one stroke than upon the opposite stroke, one of said members having a device adjustably mounted thereon and forming a stop for the other member, said device being arranged exteriorly of the casing.

8. The combination of a casing having a fluid therein, a piston in said casing, and a pair of telescopically connected members, one of which is connected to said piston, one of said members having a port by which said fluid may pass from one side of said piston to the other, the other of said members having a limited longitudinal movement

with respect to the ported member to vary the extent of opening of said port, whereby said port is open to a greater extent upon one stroke than upon the opposite stroke, said members having means adjustable outside of said casing for varying the extent of such limited longitudinal movement, said means comprising a member adjustably mounted on one of said members and forming a stop for the other member, and means 10 for preventing accidental displacement of said adjustably mounted member.

In testimony whereof, I have signed my name to this specification.

EDGAR MAYNARD CAMP.
